(57) **CLAIM**

The ornamental design for a container with extendable rod shaped solid, as shown and described.

DESCRIPTION

FIG. 1 is a perspective view of the top, front and one side of a container with extendable rod shaped solid showing my new design;

FIG. 2 is a front elevational view thereof;

FIG. 3 is a side elevational view of said one side, the opposite side being a mirror image thereof;

FIG. 4 is a rear elevational view thereof;

FIG. 5 is a top plan view thereof;

FIG. 6 is a bottom plan view thereof;

FIG. 7 is a front elevational view with the cover removed;

FIG. 8 is a top plan view thereof; and,

FIG. 9 is a bottom plan view of the removed cover.
